George B. Willcox BY
ATTORNEY

UNITED STATES PATENT OFFICE.

PHILLIP K. RUCKEL, OF SAGINAW, MICHIGAN.

PROPELLED DEVICE FOR AEROPLANES AND THE LIKE.

Application filed April 8, 1921. Serial No. 459,600.

To all whom it may concern:

Be it known that I, PHILLIP K. RUCKEL, a citizen of the United States, residing at Saginaw, in the county of Saginaw and State 5 of Michigan, have invented certain new and useful Improvements in Propelling Devices for Aeroplanes and the like; and I do hereby declare the following to be a full, clear, and exact description of the invention, 10 such as will enable others skilled in the art to which it appertains to make and use the same.

This invention relates to propelling devices adapted for use on aeroplanes, dirigible balloons or any other devices in which the propelling power is obtained by the reaction of the air against propelling planes.

My improvement also may be applied as a means for obtaining power from air in motion, as for example, a wind engine, but my present application will for purposes of better illustration be limited to a description of the device as applied to an aeroplane.

The objects of my invention are, therefore, to provide in combination with an aeroplane or similar machine, a propelling device consisting of a plurality of pivotally mounted planes adapted to be revolved in a circular orbit, the pivotal axis of each plane 30 being parallel with the common axis of revolution of all of the planes.

I also provide means whereby each of the pivoted planes can be automatically tilted into various angular positions during its 35 orbital revolution, so that the propelling planes may be made to advance flat against the wind during part of their revolution and edgewise or "feathering" during the remainder of the revolution, and that part of 40 the revolution during which they advance flatwise may be shifted to various parts of the circle of revolution by an adjusting cam device, whereby the function of the propelling planes can be quickly changed from 45 that of propelling ahead, to lifting vertically or vice versa.

A further object of my invention is to arrange the tiltable propelling planes so that if the machine falls, the propelling planes 50 will occupy such positions as to offer the maximum resistance to falling, somewhat after the manner of a parachute and, therefore, check the falling speed.

With these and certain other objects in view which will appear later in the specification, my invention comprises the devices described and claimed and the equivalents thereof.

In the drawings, Fig. 1 is a top plan view of an aeroplane embodying my invention. 55

Fig. 2 is a front elevation, broken away in part, of the aeroplane shown in Fig. 1.

Fig. 3 is a diagrammatic top plan view of the aeroplane of Fig. 1 with the propelling planes and fixed planes removed. 60

Fig. 4 is a side elevation of the aeroplane of Fig. 1, showing, diagrammatically, the propelling planes in lifting position. 65

Fig. 5 is a similar elevation, partly broken away, showing, diagrammatically, the propelling blades in their forward or driving position. 70

Fig. 6 is a fragmentary side view of one of the wheels on which the propelling blades are pivotally mounted, the annular hub of 75 the wheel being shown as rotatable around the lateral truss frame of the machine.

Fig. 7 is a part sectional side view on line 7—7 of Fig. 1, partly broken away, showing the cam track that controls the tilting or 80 feathering movement of the propelling planes, the successive positions of a propelling plane being indicated by dotted lines.

Fig. 8 is an enlarged sectional view taken on line 8—8 of Fig. 7, the view being broken 85 away in part.

Figs. 9 and 10 are respectively a plan view and an edge view of one of the roller-carrying bars that co-act with the cam track to properly shift the radial positions of 90 each of the feathering planes as they revolve.

Fig. 11 is a diagrammatic top plan view of the driving connections between the motor and the annular hubs of the wheels upon which the propelling planes are mounted. 95

The aeroplane comprises the cockpit 2 and power plant 3 and a laterally extending truss frame 4 secured to the top of the fuselage and extending to the right or left thereof, as indicated in Figs. 1 and 3.

To the outer ends of the truss frame 4 are preferably secured the usual fixed planes 5, 5, these planes being spaced apart from the fuselage 1 to permit mounting, in the space between them, the propelling and lifting mechanism to which my present invention

tion pertains. This propelling and lifting mechanism comprises primarily a set or plurality of pivotally mounted planes adapted to be revolved about the central axis of the 5 laterally extending truss frame 4, and means connected to each of said pivotally mounted planes whereby to automatically adjust or tilt the plane to successively changed radial positions during the revolution of the plane 10 about its central axis. Each plane of the set will expose its entire flat surface to the resistance of the air during a part of its revolution, and during the remainder of its travel or orbit will advance edge foremost, or approximately so, through the air, 15 so as to "feather" and offer as little resistance as possible.

Preferably the sets of propelling planes, one at each side of the fuselage, are mounted 20 as shown in Figs. 1, 2, 4 and 5, and this mounting will now be explained.

For each set of revolvable planes I provide a pair of wheels, 6 and 7, removably mounted on the truss frame 4. Carried by 25 the rims of the two wheels and pivotally mounted between them is the set of planes, as 8 to 13 inclusive. When the wheels 6 and 7 are rotated, the planes 8 to 13 are revolved in a circular orbit around the truss 30 frame 4.

Referring to Fig. 6, showing a fragmentary view of one of the wheels, as 7, it will be seen that the rim 14 carries bearings 15 upon which the planes 8 to 13 are pivoted, 35 and spokes 16 connect the rim with an annular hub 17, the interior of which forms an annular track, Fig. 8, that travels around frame 4, on sets of idler rolls 18 carried by the frame 4.

40 The plane-carrying wheels, 6 and 7, may be propelled in any suitable manner, but I prefer to apply the power at the hubs 17 of the wheels, as indicated in Figs. 6 and 8, where 19 is a sprocket wheel carried by the 45 hub 17. Upon the sprocket wheel is a drive chain 20, Fig. 5, which also encircles a sprocket 21, the horizontal location of which is indicated diagrammatically in Fig. 11. A second sprocket 22, carried by the shaft 50 of sprocket 21, is connected by a chain 23 with a sprocket 24 mounted on a jack shaft 25. This shaft also carries a sprocket 26, which is connected by a drive chain 27 with the engine or other source of power 3, so 55 that when the engine 3 is operated the jack shaft 25 with its sprockets 26 and 24 will transmit the driving power to the annular sprocket 19 through the gears 22 and 21, thereby revolving the propelling planes 60 bodily about the axis of the truss frame 4.

For the purpose of lifting the plane vertically, or nearly so, the down-coming planes, as 8 and 9, in Fig. 4, should be approximately horizontal and the up-going 65 planes, as 11 and 12, should be nearly verti-

cal, while the backwardly moving planes, as 10 and the forwardly moving planes, 13 should be as nearly horizontal as is practicable.

I, therefore, provide means for radially 70 tilting or positioning the revolving planes to automatically adjust them to successively altered radial positions during their revolution about the central axis.

Any desired or suitable mechanism may 75 be employed for this purpose, but I prefer, for purpose of illustration, to use the angular or radial adjusting devices shown in Figs. 7 to 10 inclusive.

Crosswise upon the end of the central 80 shaft 28 of each tiltable plane is secured a bar 29 having idler rolls 30 and 31 pivotally mounted at its ends.

Alongside one of the plane-supporting wheels, as 7, and spaced apart therefrom is 85 a large circular cam 32 preferably built with spokes 33 connected to an annular hub 34, this hub being mounted to rotate on idlers 35 carried by the truss frame 4, as indicated in Fig. 7.

This wheel 7 and the cam track 32 are shown in broken cross section in Fig. 8, with roller 31 in place. The cam track comprises a partially closed channel around which the idler roller 31 travels, as is shown diagrammatically by the dotted lines in Fig. 7.

90 The cam 32 may be rotated into various adjusted positions around the truss frame 4, the rotation being effected by the pilot, by means of a pinion 36 carried by frame 4 and 100 engaging an internal gear 37 mounted on the annular hub 34 of the cam. The pinion 36 may be turned by a hand wheel 38 within reach of the pilot and connected by any suitable or usual arrangement of shafts and connections with the shaft of gear 36.

Referring now to Fig. 7, it will be seen that when the bar 29 of one of the propelling planes has one of its end rollers, as 31, traveling in the track 32, the radial or angular position of the bar 29, and consequently of the plane to which the bar is attached, will be determined by the relative position and curvature of the cam 32 with respect to the axis of the propelling plane, it being remembered that the wheel and the cam are set in parallel planes slightly spaced apart, and that the arm 29 and its rollers 31 and 30 form the operating connection between the 110 tiltable planes and the cam 32.

115 The shape and position of the cam 32 being such as to give the proper tilt to the propelling planes at each part of their revolution about the central axis of rim 4, the planes will take the successive positions indicated by numerals 8 to 13 respectively in Fig. 4. It is, therefore, evident that by 120 partly rotating the cam 32 and its hub 34, the same relative tilting or feathering action of the propelling planes can be had at 130

other parts of their path of revolution. As indicated in Fig. 5, the planes that are driven rearwardly flat against the air, as 8 and 9, can by turning cam 32, be made to 5 advance flatward in a downward direction, as shown in Fig. 4. In the position of the cam shown in Fig. 4, the planes 8 and 9 tend to lift the machine vertically, while in the position of the cam shown in Fig. 5 the 10 planes 8 and 9 propel the machine forwardly. This shift of position is accomplished by the rotary adjustment of the cam 32 by means of the handwheel 38, or its equivalent. In order to produce the proper axial 15 tilting or feathering action of the planes at any part of their orbit, it is only necessary to properly shift the cam 32, and this can be done while the planes are revolving.

It will be noticed by reference to Fig. 4 20 that the outer edge of one of the planes, as 9, is outside the boundary of the cam 32 and of the wheel 6, and the same is true with reference to positions of the planes indicated by numerals 10 and 11; but in the 25 position of, say, plane 12, that edge of the plane which was outside the boundary of the wheel 6 is now within the boundary of the wheel and the opposite edge of the plane is outside the boundary.

30 To make this shift in the position of the plane while it revolves, I prefer to arrange the cam track as shown in Fig. 7, where the rollers 30 and 31 of arm 29 travel as indicated diagrammatically by dotted lines. 35 In the lower left-hand part of Fig. 7, roller 31 is shown traveling up along the cam and across the other extremity of the cam, finally leaving the cam groove at the end 39. It will also be seen that roller 30, which at 40 the lower left-hand position shown in Fig. 7 is outside the boundary of cam 32, enters the other end of the cam groove 40, crosses the first-mentioned end of the cam until it completes one revolution. Each of the 45 rollers 30 and 31 makes a revolution alternately inside the cam and then outside the cam, thereby causing each of the planes 8 to 13 to turn over on its axis 28 during the second half of each succeeding revolution. When cam 32 has been shifted from 50 the position shown in Fig. 4 to the position of Fig. 5, each of the propelling planes will turn in exactly the same manner as before, with respect to the cam 32, but their working position with respect to, say, the bottom line of the fuselage 1 will be shifted through approximately ninety degrees. When the cam 32 is in the position of Fig. 4 the machine will be lifted by the revolving planes, 55 as 8 and 9, and when the cam 32 is in the position shown in Fig. 5, the plane will be driven forward by planes 8, 9, and the succeeding planes.

When the plane is lifting, as in Fig. 4, 60 and as indicated diagrammatically at the

right-hand side of Fig. 7, I have found it advisable to provide means for preventing the roller 30 from lagging behind in the cam groove and thereby cramping the arm 29 which is carried by the shaft 28 and causing 70 unnecessary friction. To avoid such accidental crowding of the roller 30, I fix to arm 29 a wiper or guide 41 adapted to engage a fixed cam guide 42, which may be secured by means of spokes 43 to cam 32. 75

If the machine falls while the propelling planes are in the position shown in Fig. 5, that is, with planes 8 and 9 vertical, 11 and 12 horizontal and 10 and 13 inclined inwardly at the top, it will be seen that each 80 set or system of planes will act after the manner of a parachute to check the speed of falling and if the machine falls nose first with the planes in the position shown in Fig. 4, the same parachute effect will be obtained. If the machine falls in any other position it will be possible for the operator by turning handwheel 38 and cam 32, to quickly shift the set of planes into such 85 position that they will act effectively after the 90 manner of a parachute to check the velocity of falling.

While I have shown and described my device as applied to an aeroplane having a fuselage 1 and two or more fixed planes 95 5, it will be evident that my improved propelling mechanism may equally well be applied to various other uses, as for example the propelling of dirigible air ships and the like, and that it may also be employed by 100 mere reversal of its action as a wind wheel or wind mill to change wind energy into available mechanical energy.

Having thus described my invention, what I claim and desire to secure by Letters Pat- 105 ent is:

1. In an aeroplane including a fuselage and fixed planes having a lifting and propelling device comprising a set of planes, each plane pivotally supported at its ends, 110 the planes of each set adapted to be revolved about a central axis, means for so revolving said planes and positioning devices connected to each plane, said positioning devices comprising a radially projecting arm carried by each plane, a roller on each end of said arm and a cam track of approximately circular shape mounted in fixed position and adapted to receive one end of said roller, the free ends of said cam track intersecting and terminating in roller inlet and outlet channels of said cam, whereby to effect reversal 115 of said planes at each circuit around said cam.

2. In an aeroplane including a fuselage, a 125 lateral box truss projecting at each side of the fuselage, a plurality of walls each having an annular hub, idler rolls mounted at the corner of said truss and revolvably supporting said annular hub, and means for re- 130

volving said hub around said truss substantially as described.

3. In an aeroplane including a fuselage, a lateral box truss projecting at each side of the fuselage, a plurality of walls each having an annular hub, idler rolls mounted at the corners of said truss and revolvably sup-

porting said annular hub, an internal gear carried by said hub and a revolvable gear meshing with said internal gear and carried by said truss. 10

In testimony whereof, I affix my signature.

PHILLIP K. RUCKEL.
